UNITED STATES PATENT OFFICE.

ELMER A. SPERRY, OF CHICAGO, ILLINOIS.

MINING-MACHINE.

SPECIFICATION forming part of Letters Patent No. 454,500, dated June 23, 1891.

Application filed July 11, 1890. Serial No. 353,401. (No model.)

To all whom it may concern:

Be it known that I, ELMER A. SPERRY, a citizen of the United States, and a resident of Chicago, in the county of Cook and State of Illinois, have invented a new and useful Improvement in Mining-Machines, of which the following is a specification.

My invention relates to mining-machines, and has for its object to provide convenient means for digging coal and the like by means of an electric motor.

Figure 1 is a side view of the machine; Fig. 2, a plan view; Fig. 3, a vertical longitudinal section; Fig. 4, a detail of the pick; Fig. 5, a detail of the carbon-holder. Fig. 6 is a detail of the fly-wheel. Fig. 7 is a detail of the gear-wheel; Figs. 8 and 9, modifications of the clutching mechanism; Fig. 10, a modified pitman; Fig. 11, an additional modified pit-

man. A is one side of the machine, preferably made of a single casting, having the trunnion A', on which is journaled the wheel A² and the journal-box A³, on which the internal gear 25 is journaled, and the journal-box A⁴ for the short shaft A⁵. To this piece A is secured the handle B, and this portion is secured to the opposite portion of the frame, which is preferably made of a single piece, and which 30 may be indicated by the letter B'. The two are bolted together by the bolts B² B³. The portion B' is provided with the trunnion B³, on which is journaled the wheel B⁴, and to it is secured the electric motor consisting of the 35 field-magnet B⁵, pole-pieces B⁶, armature B⁷, commutator B⁸, and switch B⁹. Upon the pole-piece is secured the handle B¹⁰ and the cap B¹¹ for the exterior of the armature.

C is a shaft transverse of the frame, carrying 40 the armature at one end and the fly-wheel C' at the other and journaled at C² on the frame-piece B'. This shaft also carries the pinion C³, which meshes with the gear C⁵ on the shaft A⁵. This shaft also carries the pinion C⁴, 45 which meshes with the large spur-wheel C⁶, which has a backwardly-extending perforated journal C⁷, which is received into the box A³. A portion of the casting A serves as a casing for this gear C⁶. The frame B' extends for 50 wardly, as indicated, so as to form a suitable guide for the operative parts of the machine. Journaled within the perforated journal C⁷ is

one end of the crank D, the other end of which is journaled upon the frame or in the field-magnet, and the horizontal portion of which 55 is provided with the sleeve or pulley D', journaled by means of the balls D². About this sleeve or pulley lies the pitman-strap E, secured by the cap E' on the slide E², the lateral extensions E³ E³ of which rest upon the top 60 of the extended portion of the frame B' and beneath the guide-bars E⁴ E⁴, which are bolted to such frame. Secured to the slide E² by the key F is the reciprocating bar F', which passes through the extremity F² of such projecting frame B'. Between this extremity 65 and the slide E² is disposed the packing or elastic cushion F³, and within the outer cylindrical portion of such end is the tube F⁵, within which lies the spiral spring F⁴, about 70 the bar F. At the other extremity of the tube F⁵ is the slide F⁶, against which bears the other end of the spiral spring F⁴.

G is the pick-point secured by the key G' to the end of the tube G², the other end of which is secured by the key G³ to the end of the rod F'. The slide F⁶ engages the inner end of the tube G². This tube has the transverse slot G⁴, for a purpose hereinafter set forth. 75

J is a curved spring lying upon and within the gear-wheel C⁶, and having the hook J' at one end and rigidly secured at the other to the pin J² upon the gear. The spring J is so disposed as that its hook J' will engage the 85 lug J³, which projects from the crank D inwardly toward the gear C⁶.

The operation of this part of the device is substantially as follows: The operator by means of the handles B and B¹⁰ directs the 90 machine so as to bring the pick to the point of work. By controlling the switch B⁹ he operates the electric motor at will, the same being suitably connected with a source of electrical energy. This drives the shaft C, and 95 hence, by the intermeshing gears and pinions, the gear C⁶ in the direction indicated by the arrow. It is in Fig. 3 assumed that the spring F⁴ is extended; but as soon as the rotation brings the hook J' into engagement 100 with the pin J³ the crank, which is freely journaled at both ends, will be carried about by means of such spring J toward the position indicated in dotted lines in Fig. 3, thus re-

tracting the slide E² and compressing the spring F⁴. As soon as the parts reach the position indicated in dotted lines the expansion of the spring F⁴ will cause the crank to leave the hook, as indicated, and the pick-point will be hurled against the work. As soon as its blow is delivered its progress will be stopped by reason of the fact that the pitman E is flexible or elastic, and almost immediately it will be caught up again by the further revolution of the gear C⁶. The cushion F³ is to prevent the shock on the machine, as is also the elastic spring J.

Referring now to the details, the fly-wheel C' is composed of the exterior solid portion and the interior part K, which is keyed upon the shaft C and has the projecting ends K' K'. Between these ends and the inner projections K² K² are disposed the elastic cushion K⁴ K⁴ to make the connections between the shaft and the heavy portion of the fly-wheel elastic. In like manner the connection between the working portion of the gear-wheel C⁵ and its shaft A⁵ is made by means of the springs L L and the ledges L' L' and the parts L² L², which are keyed upon the shaft A⁵. It is obvious that either of these devices or similar devices could be employed for elastically connecting any wheel with its respective shaft. These elastic connections are exceedingly important in a machine of this character. The flexible belt E may also be replaced with the metallic flexible belt or pitman M or with the jointed pitman N, the two portions of which are pivoted together and suitably connected to the sleeve or pulley D' and by the short shaft O to the slide E². Beneath these pivoted parts is the upwardly-bearing spring S, secured upon the bottom of the frame B', so that when the blow is delivered the portions of the jointed pitman will be thrown upward, as indicated in Fig. 11.

A further modification is indicated in Figs. 8 and 9, where the end of the spring J, instead of being secured rigidly to the gear-wheel C⁶ by the pin J², is secured to the dog R, which is itself pivoted between the bifurcated ends of the support R', which is pivoted at R² to the projecting end R³ of the crank D, and is slotted at R⁴, so as to have a motion about the pivot R², the journal-trunnion R⁵ of the crank D passing through it. In this event the circular ratchet R⁶ is placed about the inner portion of the gear-wheel C⁶, and in it is adapted to play the dog R. This dog is held outwardly against such ratchet by the spring R⁷. It is clear now that the operation is substantially the same as in Fig. 3, except that the pick is taken up at once, and the process of recompressing the spring F⁴ immediately follows the delivery of the blow.

In Fig. 8 it is seen that the spring F⁴ is being compressed by the rotation of the gear C⁶, since the dog R engages the ratchet R⁶, and thus by means of the spring J retracts the elastic pitman E. Now since the end of the spring J is secured permanently to the

pin J³, the hook J' being bent over about such pin, it is clear that when the parts have reached a certain position the expansion of the spring F⁴ will force the pick forward and will carry with it the crank and dog and the spring J as long as the dog moves faster than its ratchet, and as soon as the blow is delivered and the power is taken from the elastic pitman E said dog will immediately re-engage with the ratchet R⁶ and carry the spring J around with it until the elastic pitman E is again applied to the work of compressing the spring F⁴ and retracting the pick.

T is a block supported over the commutator B⁸, and T' is a carbon on which lies the plate T², which is downwardly forced by the spring-arm T³ to keep the carbon against the commutator. This whole device is supported by the arm T⁴.

Among the important features of my invention are the several elastic connections or cushions between the operative parts of the machine, some or all of which can be used, according to the work required; also, the elastically connected and supported fly-wheel and gear-wheel; also, the flexible elastic or jointed pitman, so that the driving gear-wheel may continue its rotation after the blow is delivered without pushing upon the pick, which might be the case in the event of the use of a rigid pitman; also, the use of a spring J, whereby the connection between the reciprocating portion and the driving rotating portion is made elastic and the operative connection between the two is made intermittent.

It is evident that the parts of my machine could be greatly varied without departing from the spirit of my invention, and it is also clear that the principal features of my invention, as herein set out, are equally applicable to drills for rock and other similar substances, as well as for coal. I have found that in mining-machines and drilling-machines there is peculiar liability to various injuries on account of the rapid rotation of the parts when an electric motor is used, and the great strain upon the parts from such a rapid succession of powerful strokes delivered by a reciprocating bar, and hence the importance of the elastic and flexible connections and cushions which are devised and herein set forth.

It will be noticed in Fig. 3 that the buffer F³ is incased. This buffer is made of rubber and incased in an oil-proof case, inasmuch as oil destroys the rubber. It will also be noticed in Fig. 2 that the switch B⁹ is a double-pole switch, so arranged that the two arms move simultaneously upon the two contacts co-operating therewith. The two contacts are shown above and slightly to the left of the ends of the contacts. This switch in mining-machines is found to have a peculiar advantage, inasmuch as the mining-machine proper rests upon the ground by the wheels B⁴. The high potential that is used charges the machine more or less, inasmuch as there is leak-

age from the oil and dirt constantly accumulating upon the machine. It is found in practice that it is best to disconnect both poles at once by means of such a switch as is shown 5 at B⁹, so that the work of repair, &c., can go forward without inconvenience of having the machine continually charged.

The cap B¹¹ (see Fig. 2) is novel, inasmuch as it bears upon a projection forming an essential part of the field-magnet pole-piece, which is preferably turned concentric with the bore thereof. The projection of this pole-piece under the cap B¹¹ is shown immediately below in the opening back of the handle B¹⁰. 15 The carbon-brush holder (shown at Fig. 5) is possessed of the novel feature of having a follower T², which is connected to the frame T by a flexible wire. (Shown at the left.) This follower is pressed upon by the roller at the end 20 of the arm T³. The office of the flexible wire connecting the frame T to the follower T² is to avoid running the current to the spring which forces down the arm T³, thereby drawing the temper from the spring.

25 Having thus described my invention, what I claim, and desire to secure by Letters Patent, is as follows:

1. In a drill, the combination of a driving-motor with a driving-wheel operated thereby, 30 a device to throw the drill-bar, a catch connected therewith, and a co-operating retracting device elastically mounted upon the driving-wheel.

2. The combination of a driving-motor with 35 a device for throwing the drill-bar, and a spring and a pitman, one end of said spring adapted to be intermittently secured to the motor and the other secured to the pitman.

3. In a drill, the combination of a driving- 40 motor with a driving-wheel operated thereby, a device to throw the drill-bar, a pitman connected therewith, and a crank elastically secured to the driving-wheel.

4. In a drill, the combination of a driving- 45 motor with a driving-wheel operated thereby, a device to throw the drill-bar, a pitman connected therewith, and a crank adapted to be intermittently elastically secured to the driving-wheel.

5. The combination of a driving-motor with 50 a device to throw the drill-bar, and a connection between the two, consisting of a spring adapted to operatively connect them when the pitman tends to move slower than the opposed part of the motor and disconnect them when 55 the pitman tends to move faster.

6. In a mining-machine, the combination of a device for driving the drill-bar with a motor and a flexible pitman clamped rigidly to the cross-head connecting the motor and driving 60 device.

7. In a mining-machine, the combination of a driving device for the drill-bar with a motor and a flexible pitman between them, the pitman connected to an electric motor by means 65 of an elastic driving medium.

8. In a mining-machine, the combination of a driving device for the drill-bar with a motor and a pitman to connect the motor and device, 70 said pitman intermittently, elastically, and operatively connected with the motor.

9. In a mining-machine, the combination of a pitman with a driving-wheel of the motor, 75 said pitman adapted to be engaged by one end of a spring, the other end of which is rigidly secured to the driving-wheel of the motor.

10. In a mining-machine, the combination of a pitman with the driving-wheel of the motor, 80 said pitman secured to one end of a spring, the other end of which is intermittently operatively secured to the driving-wheel.

11. In a mining-machine, the combination of a pitman with the driving-wheel of the motor, a spring and two arms pivoted upon each other upon the driving-wheel and connected, 85 respectively, with the ends of the spring, said pitman also connected to one of these arms, a ratchet on the driving-wheel, and a dog on the other arm adapted to engage the ratchet.

12. In a mining-machine, a buffer consisting 90 of an elastic body surrounded by a cover which is substantially oil-proof.

ELMER A. SPERRY.
